UNITED STATES PATENT OFFICE.

MORTIMER J. FAIRCHILD, OF ELGIN, ILLINOIS.

SOCKET-WRENCH.

1,292,285.

Specification of Letters Patent. Patented Jan. 21, 1919.

Application filed June 19, 1918. Serial No. 240,749.

To all whom it may concern:

Be it known that I, MORTIMER J. FAIRCHILD, a citizen of the United States, residing at Elgin, in the county of Kane and State of Illinois, have invented certain new and useful Improvements in Socket-Wrenches, of which the following is a specification.

This invention relates to improvements in wrenches of the type commonly designated as socket wrenches or those wherein is embodied an actuating head designed for coöperation with a socket member properly shaped for application to the work.

It is the main and primary object of the present invention to improve the general construction of socket wrenches whereby to render them capable of greater range of use in restricted localities, and to simplify the same as far as possible in order to reduce wear in the working parts to a minimum and thereby prolong the life of the wrench.

A further object of the invention is the provision of a wrench of the class described the parts of which are so organized and related as to be easily and quickly assembled, as well as taken apart when necessity for inspection or repair may arise, and which will provide a highly compact structure to economize in space in packing and shipment.

Other objects and advantages will appear as the nature of the improvements is better understood, the invention consisting substantially in the novel construction, combination and arrangement of parts herein-after fully described, illustrated in the accompanying drawings, and finally pointed out in the appended claims. It is to be understood, however, that the present exemplification of the invention is but one embodiment thereof, and the same, therefore, is to be taken only in an illustrative, and not in a restrictive, sense.

In the drawings—

Figure 1 is a side elevation of a socket wrench constructed in accordance with the present invention and illustrated as applied to a socket, as under certain conditions of use;

Fig. 2 is a similar view taken at right angles to Fig. 1;

Fig. 3 is also a side elevation of the herein-described wrench illustrating another

condition under which the same may be used;

Fig. 4 is a sectional view, as on the line 4—4, Fig. 2;

Fig. 5 is also a sectional view, as on the line 5—5, Fig. 2.

Referring now in detail to the accompanying drawings, the numeral 10 designates the shank of the herein-described wrench. This is shaped for convenient application of the same to the hand of the user, and, therefore, tapers slightly from one end toward the other. At the latter point the end of the shank 10 is enlarged to provide a pair of parallel supporting arms 11, said arms being separated in order to form a notch 12 therebetween. The arms 11 are provided with outwardly-opening chambers 13 the inner ends of which communicate with contracted passages 14 while the outer ends of said chambers 13 are screw-threaded, as at 15, for a purpose to be presently described.

Arranged within the notch 12 is an engaging head which includes an elongated shank 16, which is cylindrical in cross-section, the ends of said shank 16 terminating in enlarged polygonal actuating plugs 17. These plugs are reversely tapered with respect to each other and are designed to be inserted into the socket with which the wrench is employed. By reason of the reverse tapering of the plugs 17 they may be alternatively used, in accordance with the direction of rotation to be imparted to the socket, as will later appear. At a point midway between the plugs 17 the shank 16 is enlarged to form an annular flange 18, and said flange is provided with a series of ratchet teeth 19 adapted to be engaged by the inner ends of oppositely-disposed reversely-arranged pawls 20. The pawls 20 are slidably mounted in the passages 14 and each is provided with an annular flange 21 of substantially the same diameter as the chambers 13. The pawls 20 are of sufficient length to extend through said chambers 13, and their outer extremities are received by perforated closure plugs 22 having screw-threaded engagement with the threads 15 of the chambers 13. Each of the plugs 22 is provided, at its outer face, with grooves or kerfs 23 for the reception of a suitable instrument, such as a screw driver, for rotating the plugs when introducing the same to and

removing them from the chambers 13. Encircling each of the pawls 20, and interposed between the flange 21 thereof and the screw plug 22 through which its outer end passes, 5 is a coiled spring 24. The tension of these springs obviously is regulated by the adjustment of the screw plugs 22, and said springs serve to force the pawls 20 inwardly and to maintain the inner ends thereof in 10 engagement with the ratchet teeth 19 of the flange 18. To effect such engagement between the pawls 20 and said teeth 19 each of the pawls has, at its inner end, a tooth 25 provided with an abrupt face 26 and an inclined face 27. The abrupt face 26 effects 15 a locking engagement between each pawl and the teeth 19, thus causing the flange 18 to move with the pawls 20, while the inclined faces 27 of said pawls will permit the latter 20 to ride over the teeth 19 to free the same from the locking engagement referred to.

Surrounding the engaging head is a pair of supporting blocks 28. The opposing faces of said supporting blocks 28 are provided with semi-circular notches 29 to permit the blocks 28 snugly fitting about and surrounding the cylindrical shank 16, and each of said blocks 28 is also provided with an interior semi-circular groove 30 for receiving 30 the ratcheted flange 18 when the blocks are assembled upon the engaging head. It will also be observed that the blocks 28 are likewise provided with openings 31 arranged in alinement with the passages 14, 35 said openings 31 receiving the inner ends of the pawls 30 and thus permitting the latter to engage the teeth 19. By reason of this construction it will be seen that the pawls 20 not only engage the ratcheted flange 18, but 40 by reason of the inner ends of the pawls passing through the openings 31 the pawls form pivots or trunnions on which the supporting blocks 28 may be rotated. This permits the engaging head to be reversed, and 45 each of the actuating plugs 17 may thus be presented to the socket with which the wrench is employed. This also provides for reversing the direction of movement of the ratcheted flange 18 it being apparent that when 50 one of the plugs 17 is engaged with the socket the pawls will rotate the ratcheted flange in one direction, while by rotating the head to present the other plug 17 for engagement with the socket the direction of the ratchet 55 teeth 19 will be reversed.

Extending longitudinally of the shank 10 is an elongated slot 32 in which is fitted a pair of handle bars 33. The adjacent ends of these bars 33 are enlarged and form offset heads 34, said heads being perforated for receiving a pivot pin 35 the inner end of which is seated in a drilled socket 36 formed at one side of the slot 32. The opposite end of the pin 35 extends into an opening 37 60 which is of greater diameter than the socket

36, said opening 37 being formed through the shank 10 at the other side of the slot 32. A screw-threaded locking plug 38 is fitted in the opening 37, and interposed between said plug 38 and the next adjacent handle bar 33 is a coiled spring 39 which 70 presses the head 34 of said bar 33 toward the head of the other bar 33. These heads are adapted to be interlocked with each other, and to this end one of the same is provided with radial ribs 40 adapted to fit within radial grooves 41 formed in the contiguous face of the other head. The spring 39 exerts its pressure to maintain the ribs 40 seated in said grooves. The folded position 80 of the handle bars 33 is illustrated in Fig. 2 wherein they appear as within the slot 32; when it is desired to use the same they are moved to the position illustrated in Fig. 1, 85 it being obvious that the spring 39 will permit relative movement of the bars with respect to each other, and thereby permit the same either to be opened or closed.

The herein described wrench is designed for use with an assortment of sockets one of 90 which is illustrated in Fig. 1 and designated by the numeral 42. The latter is illustrated as applied to a nut 43. When using the wrench one of the actuating plugs 17 is introduced into the socket 42, and by rotating the shank 10, the pawls 20 being normally urged by the springs 24 into engagement with the ratcheted flange 18, the plug and socket will be rotated. This, of course, assumes that the direction of rotation is such 95 that the abrupt faces 26 of the pawls 20 contact the teeth 19. On the reverse rotation, however, of the shank 10 the pawls 20 will ride over the teeth 19 and the socket 42 will remain stationary. If it be desired to reverse the direction of rotation of the socket 42 the wrench is removed therefrom; the engaging head is rotated 180° in order to present the other actuating plug 17 to the socket 42, and with the wrench now engaged with the socket 42, and with the shank 10 now rotated in a reverse direction, the socket 42 will 100 be rotated in the reverse direction. 105

By the construction described the shank 10 may stand in relation to the engaging head as in Fig. 1, in which position it is in alinement therewith, or it may be swung at right angles thereto, or it may be moved at any position intermediate of the two described, as illustrated in Fig. 3. In the position illustrated in Fig. 1 rotation of the shank 10 will be more conveniently effected by swinging the handle bars 33 outwardly from the slot 32 and into the position illustrated in Fig. 1. In doing this slight pressure is exerted on the handle bars 33 to separate the heads 34 thereof, and when they are moved to the desired position the spring 39 will reassert itself, forcing the ribs 40 of the one member into the grooves 110 115 120 125 130

41 of the other, and thus maintain the handle bars at the desired angle in relation to each other.

I claim:

5 1. A wrench of the class described, comprising a shank, a ratcheted engaging head pivotally mounted therein, and a plurality of pawls carried by said shank for engaging with the ratcheted head, said pawls forming 70 trunnions on which said engaging head rotates to position the head for engagement with a socket under reverse directions of movement.

10 2. A wrench of the class described, comprising a shank, a ratcheted engaging head pivotally mounted therein and provided with reversely arranged socket-engaging members, and a plurality of pawls carried by said shank for engagement with said ratcheted 75 head, said pawls forming trunnions on which said engaging head rotates to position the head for engagement with a socket under reverse directions of movement.

15 3. A wrench of the class described, comprising a shank provided with oppositely arranged parallel arms, a ratcheted engaging head pivotally mounted between said arms, and a plurality of pawls carried by 80 said arms and projecting inwardly therefrom for engagement with said ratcheted head, said pawls forming trunnions on which 85 said engaging head rotates to position the head for engagement with a socket under reverse directions of movement.

20 4. A wrench of the class described, comprising a shank provided at one end with a pair of parallel arms, a ratcheted engaging head arranged between said arms and provided with reversely arranged actuating 90 plugs, and a plurality of pawls carried by 95 said arms and projecting inwardly therefrom for engagement with said ratcheted head, said pawls forming trunnions on which said engaging head rotates to position the head for engagement with a socket under reverse directions of movement.

25 5. A wrench of the class described, comprising a shank provided at one of its ends with a pair of parallel supporting arms, 100 a ratcheted engaging head arranged between said arms, a plurality of supporting blocks also arranged between said arms and embracing said engaging head, and a plurality of pawls carried by said arms and 105 projecting through said supporting blocks for engagement with said ratcheted head, said pawls forming trunnions on which said engaging head rotates to position the head for engagement with a socket under reverse 110 directions of movement.

30 6. A wrench of the class described, comprising a shank provided at one of its ends with a pair of parallel supporting arms, a ratcheted engaging head arranged between 115 said arms, a plurality of pawls slidably

mounted in said arms and projecting inwardly therefrom into engagement with said ratcheted head, and means for normally forcing said pawls into said engagement, said pawls forming trunnions on which said 70 engaging head rotates to position the head for engagement with a socket under reverse directions of movement.

7. A wrench of the class described, comprising a shank provided at one of its ends 75 with a notch, an engaging head arranged in said notch, a ratchet carried by said head, and a plurality of pawls carried by said shank and projecting into said notch and into engagement with said ratchet, said 80 pawls forming trunnions on which said engaging head rotates to position the head for engagement with the socket under reverse directions of movement.

8. A wrench of the class described, comprising a shank provided at one of its ends with an opening, a ratcheted engaging head arranged in said opening, a pair of supporting blocks surrounding said ratcheted head and serving to maintain the latter within said opening, and a pair of inwardly extending pawls carried by said shank and projecting into said opening, the inner ends of said pawls being extended through said supporting blocks for engagement with said 90 ratcheted head at opposite sides thereof, and means for normally forcing both said pawls 95 inwardly into such engagement.

9. A wrench of the class described, comprising a shank provided at one of its ends 100 with an opening, said shank having oppositely disposed chambers arranged adjacent to said opening and in communication therewith, a ratcheted engaging head arranged in said opening, slideable pawls mounted 105 in said chambers and having their inner ends projected into said opening for engagement with said ratcheted head at opposite sides thereof, springs arranged in said openings for normally forcing said pawls inwardly 110 and into engagement with said ratcheted head, and means for retaining said springs within said chambers.

10. A wrench of the class described, comprising a shank provided at one of its ends 115 with a notch, said shank being also provided at opposite sides of said notch with a plurality of chambers in communication with the notch, a ratcheted engaging head arranged in said notch, a plurality of inwardly 120 extending pawls mounted in said chambers and having their inner ends projected into said notch for engagement with the ratcheted head, springs arranged in said chambers and normally forcing the pawls into engagement with said ratcheted head, and a closure plug arranged in each of said chambers 125 for retaining the springs therein.

11. A wrench of the class described, comprising a shank provided with an elongated 130

4
slot, socket-engaging means associated with said shank, a pin extended across said slot, a pair of handle bars arranged in said slot and pivotally mounted on said pin for relative movement with respect to each other, and means for maintaining said handle bars in relative positions of adjustment.

12. A wrench of the class described, comprising a shank provided with an elongated slot, socket engaging means associated with said shank, a pair of handle bars concentrically pivoted within said slot for relative movement with respect to each other, means for frictionally maintaining said handle bars in relative positions of adjustment, and yielding means for holding said bars against displacement from adjusted position.

13. A wrench of the class described, comprising a shank provided with an elongated slot, socket engaging means associated with said shank, a pin extended across said slot, a pair of handle bars arranged in said slot

and capable of relative movement with respect to each other, the contiguous portions of said handle bars being enlarged to provide heads, said heads being perforated for receiving said pin whereby to pivot said bars thereon, radial ribs carried by one of said bars, the opposing face of the other bar being grooved for the reception of said ribs, said ribs and grooves effecting an interlocking relation between said bars to hold the same in relative positions of their adjustment, and a spring surrounding said pin and exerting its pressure to maintain the engaging portions of said bars against relative movement.

In witness whereof I have hereunto signed my name in the presence of two subscribing witnesses.

MORTIMER J. FAIRCHILD.
